UNITED STATES PATENT OFFICE.

FREDERICK W. HAAS, OF PITTSBURGH, PENNSYLVANIA.

WATER-COOLING TOWER.

1,253,234.

Specification of Letters Patent. Patented Jan. 15, 1918.

Application filed November 2, 1916. Serial No. 129,065.

To all whom it may concern:

Be it known that I, FREDERICK W. HAAS, a citizen of the United States, residing at Pittsburgh, in the county of Allegheny and State of Pennsylvania, have invented new and useful Improvements in Water-Cooling Towers, of which the following is a specification.

My invention relates to apparatus for cooling water or other liquid.

The object of this invention is to provide a simple, cheap, and efficient apparatus by which liquid may be cooled by being converted into a finely divided state and by causing a natural or forced draft of air to pass through the same. This invention also provides a novel means for causing the fluid to be finely divided. Other objects will appear hereinafter.

Referring to the accompanying drawings, Figure 1 is a front elevation of a cooling tower embodying the principles of the present invention, portions being broken away; Fig. 2 a horizontal section, on an enlarged scale, of a portion of the said invention the section being taken on the line 2—2, Fig. 1, parts being shown in plan; Fig. 3, a perspective view showing a portion of the outer face and the sides of one of the louvers which I employ; Fig. 4, a cross-section on an enlarged scale showing a portion of the pan *m* and adjacent parts the section being taken on the line 4—4, Fig. 2, the sprayers being shown in side elevation; Fig. 5, a section of one of the sprayer devices which I employ with the pan *m*; Fig. 6, a section of a modification of my spraying device; and Fig. 7, a detail view showing a portion of one of the front louvers. Fig. 8 is a vertical section showing a second modification of my invention, and Fig. 9 is a top plan view of Fig. 8.

I have shown my cooler with rectangular sides and ends, but the shape thereof may be varied to suit the preference of the person for whom it may be designed. I have shown the cooler having four superposed chambers *a*, *b*, *c*, *d*. The sides of each chamber are largely made up of louvers *e* fitted into recesses in the vertical studding or strips *f* arranged between the ends of the chambers and connected to the beams or horizontal members *g* which have their ends connected to the corner posts *h*.

The louvers on all sides, except one, of the cooler have the slats *i* preferably immov-

ably connected to the sides thereof. On the front side I make the slats of the louvers rotatable on pivots *k* at their ends so that these louvers may be open or closed like the well known type of house blinds or shutters employing rotatable slats operated by a vertical bar *j*, by which all the slats in the edges of the slats. The slats *i* of each of the front louvers are pivotally connected to a vertical bar *j*, by which all the slats in the louver may be simultaneously rotated on their end pivots *k*.

Preferably one of the front louvers for each chamber is a door or in a door which may be swung on hinges, as *l*, to permit an attendant to enter the several chambers. The hinges are preferably arranged so as to allow these louvers to swing inwardly.

The upper chamber *a* has the pan *m* which closes its upper end. A large number of downwardly tapering sprayer tubes *n* are suspended in holes in the bottom *o* of the pan. Each tube (Fig. 5) has a short distance below its lower end the convex water-spreader or deflector *p* secured on the lower end of the rod or stem *q* which extends down centrally through the tube *n* and has its upper end secured rigidly to the cross-piece *r* secured to the tube. The spreader stem *q* may, as shown on Fig. 6, have the ring *s* at its upper end to hold the spreader at the selected distance below the tube *n*. This stem has the spider or spacer *t* to hold the stem centrally in the tube. By inserting a finger in the ring *s* the stem and spreader may be moved up and down to dislodge any matter which may be on the spider or spreader.

Pans *m'*, *m²*, *m³* with spraying devices like those of the pan *m* are placed between the chambers *a* and *b*, *b* and *c*, and *c* and *d*, respectively.

An exhaust fan *u* is placed centrally in the front of each chamber, though the fan for the lowest chamber may be omitted, if desired.

Water falls from each of the pans *m*, *m'*, *m²* into the next pan below, the water from the bottom pan *m³* falling into any suitable receptacle in or below the chamber *d*. The water falls from the sprayer tubes *n* upon the convex spreaders *p* by which it is formed into exceedingly thin inverted bowl-like bodies, which break at their edges into a very fine spray. The front louvers being all closed, the fans cause air to pass through

the side and rear louvers and through the falling spray whereby the water which has been cooled by its expansion into spray is still further cooled by the currents of air. 5 The air exhausted from the chambers by the fans carries a large amount of heat from the chambers, thereby causing the water condensed from the spray to be cooler than it would be without the fans. The water 10 becomes successively cooler as it falls from the several pans. The number of pans will vary according to the degree of cooling required.

The front louvers may all be open and the fans allowed to remain still, and natural 15 draft be relied on to cool the falling spray, when the air is sufficiently cool and has sufficient force to cause drafts to pass through the cooler.

Referring now to Figs. 8 and 9, I show 20 a section of the top chamber a' and a portion of the next lower chamber b' . The chambers are substantially alike so that I will describe chamber a' only, which is in the form of a frustum of a pyramid, the 25 louvers e' being secured between the adjacent inclined studding k' , or between adjacent studding k' and posts h' . The upper pan m^a is supported at the top of the chamber a' and is provided with the spraying 30 devices n having the spreaders p .—The pan m^b is placed at the bottom of the chamber a' and preferably extends to the inner faces of the louvers.

The chamber b' is immediately below the 35 chamber a' . The bottom of the chamber a' extends horizontally at all sides beyond the upper end of the chamber b' . The spraying devices n are put in only the portion of the pan m^b which lies directly over the 40 space inclosed by the upper end of the chamber m^b . The apparatus shown in Figs. 8 and 9 obviously prevents more of the spray from being blown out of the chambers by a

strong wind than the apparatus shown in Figs. 1 and 2 because of the increasing size 45 of the chamber downwardly. The spray falling from the upper pan can travel considerably laterally and still fall into the next lower pan where the louvers or side walls of the apparatus are inclined as shown on Figs. 50 8 and 9. I have shown Figs. 8 and 9 without fans but they obviously may be used. It will be understood that any desired number of chambers like a' and b' may be superposed. 55

I claim—

1. In a liquid cooling tower, a plurality of superposed chambers, some of the sides of the chambers being provided with louvers, air-exhausting means at one of the 60 sides of each chamber, a liquid-receiving pan at the top of each chamber, and sprayer devices in the bottom of each pan.

2. In a liquid cooling tower, a plurality of superposed chambers, some of the sides of the chambers being provided with louvers and the louvers on one of the sides being closable, air exhausting means at a side having a closable louver, a liquid-receiving pan at the upper end of each of the chambers, and means for converting the liquid 65 into spray as it falls from the pans. 70

3. In a liquid cooler, a plurality of superposed chambers, each in the form of a frustum with its smaller end up, downwardly 75 and inwardly inclined louvers on the sides of the frustum, liquid receiving pans at the tops of the chambers, and devices in the bottoms of the pans restricted to the area inclosed by the top of each chamber and 80 adapted to convert the liquid into spray as it falls from the pans.

Signed at Pittsburgh, Pa., this 21st day of October 1916.

FREDERICK W. HAAS.
